TELEPHONE-EXCHANGE SYSTEM.

1,242,655.

Specification of Letters Patent.

Patented Oct. 9, 1917.

Application filed February 29, 1916. Serial No. 81,201.

To all whom it may concern:

Be it known that I, HENRY P. CLAUSEN, a citizen of the United States, residing at Mount Vernon, in the county of Westchester and State of New York, have invented 5 certain new and useful Improvements in Telephone-Exchange Systems, of which the following is a full, clear, concise, and exact description.

10 This invention relates to improvements in telephone exchange systems, and more particularly to a system for relieving a telephone switchboard operator of certain speaking processes in the answering and 15 handling of telephone calls.

The principal object of this invention is to provide an automatic speaking means, as a 20 teletypewriter or a phonograph adapted to meet a calling subscriber at the proper moment with a query "number please" or an equivalent phrase, also for speaking other phases ordinarily required to be spoken by an operator in the course of the regular 25 work at a telephone switchboard.

30 In accordance with this invention, talking machines included with the equipment of a telephone switchboard are adapted to be connected with a link-circuit for a predetermined interval of time, immediately in 35 advance of the instant an operator's telephone set will be included with the same link circuit, all in an automatic manner and following the inclusion of a link circuit with a subscriber's line for the purpose of answering 40 a call thereon. The talking machine, in this case, speaks the phrase "number please" which will be heard by the calling subscriber. By a system of properly timed circuit controlling mechanisms, as plain and 45 retarded relays, the operator's telephone set is connected to a link circuit at an instant to slightly overlap the latter part of a mechanically spoken phrase, in order that the operator may know that such phrase has been spoken to the calling subscriber, and accordingly, the operator merely listens to receive 50 the number of the subscriber wanted.

In the drawing, Figure 1 represents diagrammatically two subscribers' line circuits 55 terminating on a switchboard position provided with equipment suitable for connecting subscribers' lines for communication, and also talking machine apparatus suitable for carrying out the present embodiment of this invention. Fig. 2 illustrates in a simi-

lar manner additional circuits at the same switchboard position. The respective circuit relation of the apparatus in Fig. 1 and Fig. 2 will be apparent when the sheets one and two of the drawings are placed side by side in numerical order. In Fig. 1, that portion of the equipment common to a plurality of link circuits at the switchboard position is, for the sake of clearness, shown to the right of a dotted dividing line. 60

In the present embodiment of this invention, a plurality of link circuits at a switchboard position are provided with a relay common to the position, which makes it possible for an operator to include a second link 70 circuit to answer another subscriber's line during the time the answering of a first subscriber's line is taking place by means of another link circuit. Automatic relay action takes place when the connection of the 75 first subscriber is completed, thereby disconnecting the operator's telephone set from that link circuit, and connecting it to the second link circuit on which the other subscriber is waiting to be answered. By means 80 of a second relay, also common to the position, a talking machine is adapted to be connected to the waiting link circuit on the instant that a ringing key or button on the calling end of the first connection is depressed. During the time required by suitably conditioned relays in transferring the 85 connection of the operator's telephone set from the first to the second link circuit, and in disabling the circuit of the talking machine relay, the greater portion of the phrase "number please" will have been automatically spoken to the waiting subscriber, and after the speaking of this phrase has been completed, the automatic speaking means is 90 disconnected, leaving the operator free to hear the request of the calling subscriber. Manually operated keys are also employed to control talking machine circuits, adapted to be connected at the proper time to speak the 95 answering phrase above mentioned, also other phrases, as, "I am ringing your party," "your party does not answer," "operator," "what number are you calling, please," "deposit a (certain) coin in the slot, please," 100 etc. An automatic circuit interrupting means also provides that the supervisory signal of a link circuit, waiting in the answering position on a subscriber's line, and a pilot signal will be flashed in a character- 110

istic manner during the waiting period. Similar flashing also takes place in case the originating subscriber on a completed connection may attempt to attract the attention 5 of the operator, as in making a recall.

In more specifically describing the operation of this system, the processes necessary in the handling of a connection between the stations A and B, in which it will be assumed that the call originates at the station 10 A, will be traced, and during the time an operator at the switch board position E is answering this call, it will be further assumed that a second call is received from a subscriber's station C in a desire to secure a 15 connection, say, with a subscriber's station D. It will be understood that subscriber line equipment similar to that shown at A and B is present with the switchboard jacks 20 at the locations C and D, respectively.

On the origination of the call at the station A, a line lamp signal 3 will be displayed, whereupon an operator at the position E inserts a plug 4 of a link circuit 1 25 in a jack 5 of the line circuit A. Talking battery through a double wound supervisory relay 6 is thereby supplied to the main conductors of the link circuit 1, thence over the tip and ring contacts of the plug 4 and the 30 jack 5 to the line circuit A for the subscriber's instrument thereon. A cut-off relay 10 for disconnecting the line relay 11 of the line A, to thereby extinguish the line lamp 3, is operated by battery current supplied 35 over the sleeve or signal circuit contacts of the plug 4 and the jack 5 from a branch circuit, one limb of which may be traced through the grounded battery, the contacts 13 of a relay 12, contacts 17 of a common 40 or master relay 16, the winding of a listening relay 20, thence to the sleeve contact of the jack 5. The second limb of this branching circuit extends through the battery, contacts 27 of the relay 26, contacts 8 of the 45 relay 6, a resistance unit 32, thence to form a junction at the sleeve contact of the plug 4 with the circuit limb first traced. In this position, the supervisory relay 6, cut-off relay 10, master relay 16, and the listening relay 20 are all retained operated and a supervisory lamp 31 is extinguished, due to its 50 being shunted by the circuit through the contacts 8 of the relay 6 and the contacts 27 of the relay 26. The energizing circuit of the relay 16 is completed through the contacts 22 of the relay 20. The operator's telephone set 33, now connected to the main conductors of the link circuit 1 through the bus conductors 34 and 35, and the contacts 55 24 and 25 of the listening relay 20, permits the operator to talk with the subscriber at A. Let it be assumed further that at this instant, or during the time the plug 4 was being inserted in the jack 5, a call is also 60 received from a subscriber assumed to be

connected with the jack at C. The operator may thereupon place a plug 92 of a link circuit 2 in the jack 93 of the line C. Although a circuit is thereby completed through the battery, the contacts 83 of the 65 relay 82, the contacts 91 of relay 89, a resistance unit 88, the sleeve contacts of the jack 92 and the plug 93, thence to earth through the winding of a cut-off relay 94; the listening relay 76, associated with the 70 link circuit 2, does not operate at this time, owing to the separation of the contacts 18 of the master relay 16. The operator's set 33 is accordingly not included with the link circuit 2, but remains connected with the 75 first link circuit 1. On the operator being informed from the station A that a connection is desired with the station B, the calling plug 36 of the link circuit 1 is inserted in the jack 37 of the line B. Thereupon, current from the battery through the supervisory lamp 38, the contacts 41 of the supervisory relay 40, which short-circuits a resistance unit 39, completes a circuit over the 80 sleeve or signal circuit contacts of the plug 36 and the jack 37, thereby lighting the lamp 38 and operating a cut-off relay 43 associated with the line B. The relay 12, included through the serially connected contacts 106 and 109 of keys 105 and 108, 85 respectively, in parallel with the lamp 38 is also operated; the lamp 38 is not extinguished, however, as the winding of the relay 12 is of relatively high resistance. A push-button type ringing key 44 when fully 90 depressed, which position is non-locking, acts on the plate 46 to close the contacts 47 and 48, in addition to closing the contacts 49 and 50. When pressure is removed from the plunger 44, it is moved by a retractile 95 spring (not shown) to an intermediate position at which it is suitably engaged and held locked by the plate 46. In this position the contacts 49 and 50 are retained closed while the contacts 47 and 48 remain open. Therefore, immediately following the insertion of the plug 36 in the jack 31, the operator momentarily depresses the ringing key 100 plunger 44 to its lowest position. This results in initially operating a ringing relay 105 51 of the link circuit 1 over a path formed through the battery, contacts 9 of the supervisory relay 6, the winding of the relay 51, and the contacts 47 of the ringing key to earth. The contacts 56 of the relay 51 110 close a locking circuit, which further extends through the contacts of a trip relay 57, in substitution of the contacts 47 of the ringing key, thereby retaining the relay 51 energized after the contacts 47 are separated on the plunger 44 being released to the intermediate or locking position. Ringing current from a grounded source, indicated by a plus and minus sign, now completes circuit 115 through the contacts 50 of the ringing key, 120

the winding of the trip relay 57, contacts 54 of the relay 51, thence over the connection to the substation bell at B, returning over the contacts 53 of the relay 51 and the contacts 49 of the ringing key 44, to earth. When this calling signal is answered by the removal of the telephone receiver from its switch hook at the station B, the reduced resistance of the line circuit loop due to the 10 telephone set being in the talking position thereon allows an increase in the ringing current quantity through this circuit, thereby operating the trip relay 57, whereupon the momentary separation of its contacts 15 results in deenergizing the ringing relay 51. The talking conductors of the link circuit 1 are now connected through the contacts 52 and 55 of the relay 51 with the plug 36, and the separation of the contacts 56 of this relay prevents its reoperation after the contacts of relay 57 are closed, following the deenergization of the latter relay which results from the releasing of the relay 51. Talking battery is supplied to the telephone 25 set at B through the double wound supervisory relay 40 and the resulting operation of this relay extinguishes the supervisory lamp 38 through the substitution of the resistance unit 39 for this lamp, as effected 30 by the separation of the contacts 41 and the closing of the contacts 42 of the relay 40.

Returning to the instant the ringing key 44 was fully depressed in initiating the ringing operation on the line B, the contacts 35 48, closed by this key, effect through a bus conductor 64 the operation of a relay 58, the contacts 59 and 60 of which connect the speaking circuit of a talking machine 63 to the common or bus conductors 61 and 62. 40 The bus conductors in turn connect through the contacts 71 and 72 of a relay 70 to the main conductors of the link circuit 2. The relay 58 is adapted to release slowly and is so timed in this respect that the talking machine 63 will only be included with the link circuit 2, a sufficient time for speaking the phrase "number please," which will be heard by the party waiting to be answered at C. The operation of the relay 12 which took 45 place at the time the plug 36 was inserted in the jack 37 disconnects, by the separation of its contacts 14 and 15, the bus conductors 61 and 62 of the talking machine from the link circuit 1. The separation of the contacts 13 50 of the relay 12 disconnects the holding circuit of the listening relay 20, which thereupon restores to disconnect the operator's telephone set 33 at the contacts 24 and 25, from the link circuit 1, also to disconnect 55 the master relay 16 at the contacts 22, and through the contacts 21, prepares a circuit for the flashing control relay 26, the operation of which will presently be described. The releasing of the relay 16 completes a 60 circuit from the battery through the contacts 65

73 of the relay 70, conductor 74, the contacts 18 of the relay 16, conductor 75, the winding of the relay 76, to a junction with the sleeve conductor of the connection, thereby establishing the relay 76 in parallel 70 with the resistance 88. After being initially operated over the circuit just traced, the relay 76 is self-locked over its own contacts 79, now substituted for the contacts 18 of the master relay 16, which operated in response to the connecting of battery to the bus conductor 80', through the contacts 78 of the relay 76, and the closing of the contacts 80 and 81 of the latter relay connects the bus conductors 34 and 35 to include the 80 operator's telephone set 33 with the link circuit 2. During the time the relay actions are taking place, due to the inclusion of the calling end of the link circuit 1 with the line B, and to the momentary depression of the plunger 44 of the ringing key, as just described, the talking machine 63 will have been connected with and spoken the answering phrase to the calling subscriber at C, in the manner described. The relay 58 is provided with a copper secondary, as shown, for the purpose of delaying its release until the talking machine will have completed speaking the desired phrase. (It will be understood that a dash-pot relay or other 90 suitably retarded circuit controlling device may be employed if necessary to permit the speaking of phrases of greater length.) Without the necessity of speaking, the operator accordingly receives from the party 100 at C the number of the subscriber's line wanted, which in this case, as assumed, is that of the subscriber's line D. A calling plug 95 is then inserted in the jack 96, which, as mentioned, may be considered to 105 represent a completely equipped line similar to that shown at B. The relay action taking place from this connection corresponds with those already described when the link circuit 1 was included with the line B. For 110 the link circuit 2 the relay 70 acts through the separation of its contacts 73 to disconnect the listening relay 76, which in turn disconnects the master relay 16, the bus conductors of the talking machine 63, being disconnected by the separation of the contacts 71 and 72 of the relay 70. A ringing key 98 is used to operate a relay 100 and to set up 115 circuit connections for applying ringing current to the line D, in a manner similar to that described for the corresponding operation of the key 44 on the connection at the line B. This ringing operation also closes the contacts 65 to reoperate the relay 58 for including the talking machine 63 120 with another link circuit which may have been connected for answering a third subscriber's line.

During the time the stations A and B are joined through the link circuit 1, the relays 130

6, 10, 12, 43 and 40 are energized, and corresponding relays 89, 94, 70, 97 and 99 are retained energized by the link circuit 2 over which the lines C and D are joined. The 5 condensers shown in each of the main conductors of the link circuits 1 and 2 are for the well-known purpose of separating the battery current supply with respect to the answering and calling end of the link circuits.

10 In order to describe the operations by which the supervisory signal and a pilot signal are flashed during the time a second call is waiting to be answered, let it be assumed that the connections described have 15 only progressed to the stage at which the answering ends of the link circuits 1 and 2 are included with the line circuits A and C, respectively, the relays 6, 10, 16 and 20 20 standing operated for the A party, and the relays 89 and 94 held operated for the C party. The listening relay 76 of the link circuit 2 being inert, its contacts 77 close battery current through the winding of a 25 flashing control relay 82, its contacts 85, the contacts 90 of the supervisory relay 89, thence over the sleeve contacts of the plug 92 and the jack 93, to earth, through the winding of the cut-off relay 94. The circuit 30 just traced is only present momentarily during the difference in time between the closing of the sleeve contacts at the plug 92 and the jack 93, and before the engagement of the tip and ring members thereof, to complete 35 the circuit of the main conductors of the link circuit to the line loop C. This results in delaying the operation of the supervisory relay 89 until the plug 92 is fully seated in the jack 93. An impulse of current, over 40 the sleeve circuit traced, initially operates the relay 82, following which, its contacts 86 close circuit in advance of the separation of its contacts 85, thereby establishing the relay 82 in parallel with the lamp 87. The 45 closing of the contacts 84 of the relay 82 separates its contacts 83, thereby disconnecting direct battery from the contacts 91 of the supervisory relay 89, and substituting therefor, battery supplied through an in- 50 terrupter 101, by way of a bus conductor 69 and a low resistance pilot-signal relay 102. The supervisory relay 89 finally operated, removes a short circuit by the separation of its contacts 90, from around the resistance 55 unit 88 and on the closing of the contacts 91, of this relay the series formed by the pilot relay 102 and the interrupter 101 is connected in parallel with the supervisory lamp 87. During each instant the battery circuit is 60 opened at the interrupter 101, the lamp 87 is lighted, and the relay 102 being inert at such times, a pilot lamp 103 is extinguished. When the circuit is closed through the interrupter 101, the lamp 87 is extinguished, 65 due to its being bridged by the low resist-

ance winding of the relay 102. This relay, operated by this shunting current, completes a circuit through its contacts, whereby the pilot lamp 103 is lighted. It is accordingly apparent that the supervisory lamp 87 and 70 the pilot lamp 103 will be flashed in opposite phase, and in unison with the operation of the interrupter 101. This characteristic flashing will continue until the calling end of the link circuit 1 is connected to the line of 75 the subscriber wanted, whereupon the relay actions, already described, take place to operate the listening relay 76 of the link circuit 2, and by the separation of its contacts 77, releases the flashing control relay 82. 80 The separation of the contacts 84 and the closing of the contacts 83 of the relay 82, respectively, disconnect the circuit from battery through the interrupter 101 and the relay 102, and substitutes therefor direct 85 battery to the contacts 91 of the supervisory relay 89, thereby shunting and extinguishing the supervisory lamp 87.

90 In order to describe the operations which take place in flashing a supervisory lamp and a pilot lamp, in response to a recall set up by a subscriber who may have originated a call under connection, let it be assumed that during the time the connection is present, as described, between the stations A and B, 95 that the receiver is momentarily restored to its switch hook at the station A. The resulting momentary release of the supervisory relay 6, and the corresponding separation of its contacts 8, disconnects the battery 100 shunt around the relay 26, which relay thereupon operates through a circuit from battery, the contacts 21 of the relay 20, its own contacts 29 and the contacts 7 of the relay 6. The separation of the contacts 27 105 of the relay 26 disconnects the battery supply from the contacts 8 of the relay 6, and the closing of the contacts 28 of the relay 26 substitutes a battery supply through the interrupter 101 and the pilot-control relay 102. The supervisory lamp 87 and the pilot lamp 103 will accordingly be flashed by the 110 operation of the interrupter 101 in a manner similar to that described for the flashing operations for the waiting connection on the 115 link circuit 2. In order to answer this recall, the operator may either remove the calling plug 36 from the jack 37, or depresses a proper phase key as 105 or 108, 120 whereupon the relay 12 releases and the closing of its contacts 13 initially operates the listening relay 20, which in turn operates the master relay 16, thereby including the operator's telephone set 33 with the link circuit 1, and also guarding the telephone set 125 against improper inclusion with another link circuit. Separation of the contacts 21 of the relay 20 deenergizes the flashing control relay 26, the contacts 28 and 27 of which respectively disconnect the inter- 130

rupter 101 and the relay 102, substituting therefor direct battery to the contacts 8 of the relay 6.

Other applications of a talking machine, 5 for the purpose of relieving the operator of certain speaking processes, may be specifically described as follows:

When answering a call the operator may momentarily depress a non-locking key 104, 10 connected from the bus conductor 64 in parallel with the contacts 48 of the ringing keys, to operate the relay 58, and thereby include the talking machine 63 with the link circuit used for the purpose described in answering 15 the call. By means of a manually operated key 105, a second talking machine may be included with a link circuit at the time two lines are joined thereby. This may be illustrated by assuming that the lines A and B 20 are joined through the link circuit 1, as already described. By depressing, say, the key 105, its contacts 106 permit the relay 12 to release, and the closing of its contacts 13 causes the operation of the listening relay 25 20, while the contacts 14 and 15 connect the bus conductors 61 and 62 with the link circuit 1. Now, assuming that a second talking machine, similar to 63, provided with a relay corresponding with the relay 58 is connected 30 to the conductor 107 of the key 105, for including the speaking circuit of the second talking machine with the bus conductors 61 and 62, it will be apparent that a phrase spoken by the second talking machine would 35 be heard on the connected circuits. This talking machine and its associated relay are diagrammatically illustrated by the dotted rectangle 111. At this time the phrase may be "I am ringing your party." A third key 40 108, if depressed, may, through the separation of its contacts 109, and the control of a third talking machine equipment diagrammatically illustrated by the dotted rectangle 112, also similar to that shown at 58 and 63, 45 over the conductor 110, cause another phrase to be spoken on the connection, say, "Your party does not answer." In this manner, by the employment of a plurality of talking machines, this system may be extended to 50 include practically all of the routine phrases otherwise required to be spoken by an operator, or for saying "the line you are calling is busy." To further economize an operator's time, slow releasing relays similar to the relay 58 may be placed under control of the 55 keys 105 and 108, thereby only necessitating a momentary operation of these keys for certain phrases; the slow releasing relays in this case being adapted to retain a relay, as 60 12, deenergized for a period of time sufficient for the speaking of the desired phrase.

With regard to the advantages of this system, it will be mentioned that during the time phrases are being automatically spoken, 65 an operator may devote her attention to

other operating matters, such as completing other connections, removing such connections, making out any necessary tickets, etc. A considerable gain in general operating efficiency is also possible with this system 70 due to the uniformity, distinctness of enunciation, and correctness of inflection present with the automatically spoken phrases.

Referring to the ringing keys shown in this system, it will be understood that the 75 plungers 44 and 45, grouped as shown, provide for individual ringing on two party lines whereon each bell is connected from a respective one of the line conductors to earth. It will be understood, however, that additional ringing key plungers similar to 44 and 45 may be included in these groups, and a system of either pulsating or harmonic ringing currents employed in securing selective ringing on lines equipped with a correspondingly increased number of stations. 80 85

Although several batteries have, for convenience, been shown in the drawing, it will be understood that these several sources of current may be, and preferably are, one and the same battery. It will also be understood 90 that the talking machines described in this system are equipped with suitable operating or motor means.

What is claimed is:

1. In a telephone system, subscribers' lines, link circuits adapted for connection with said subscribers' lines, an operator's telephone set, means for associating said set with said link circuits, a speech reproducing device adapted to request information from the calling subscriber, and means independent of such telephone set associating means and selectively controlled by the operator for associating said speech reproducing device with said link circuits. 95 100 105

2. In a telephone exchange system, subscribers' lines, link circuits for interconnecting said subscribers' lines, an operator's telephone set, means for automatically including said operator's set with said link circuits, a talking machine, and means for automatically including said talking machine with a link circuit in advance of and in a manner to overlap the moment at which the operator's set will be included with the link circuit. 110 115

3. In a telephone exchange system, subscribers' lines, link circuits for interconnecting said subscribers' lines, an operator's telephone set adapted to be included with said link circuits, a plurality of talking machines, means for selectively including said talking machines to speak on said link circuits, and switching means for automatically including a certain one of said talking machines with a link circuit when the link circuit is jointed to only one of said subscribers' lines. 120 125

4. In a telephone exchange system, sub- 130

- scribers' lines, link circuits for interconnecting said lines, an operator's telephone set, a plurality of talking machines adapted to speak different predetermined phrases, and 5 means for including said operator's set and any selected one of said talking machines with said link circuits in unison or overlapping phase with the moment of connection of said operator's set with the link circuit.
- 10 5. In a telephone exchange system, subscribers' lines, link circuits for interconnecting said lines, signals and pilot signals for said link circuits, means for automatically flashing said signals, an operator's telephone set, means for automatically including said operator's set with said link circuits, means to prevent the inclusion of said operator's set with more than one of said link circuits at the same time, a talking machine, and 15 means adapted to automatically include said talking machine with a link circuit in advance and overlapping phase with the inclusion of the operator's telephone set with the same link circuit.
- 20 6. In a telephone exchange system, subscribers' lines, link circuits for interconnecting said lines, an operator's telephone set, automatic switching means adapted to include said operator's set with a first used link circuit and to exclude said telephone set from a secondly used link circuit, a talking machine; and automatic switching means adapted to exclude said telephone set from the first used link circuit and include said 25 talking machine with said secondly used link circuit, for a predetermined period, and to include said operator's telephone set with the secondly used link circuit to overlap the period during which the talking machine is 30 included with the secondly used link circuit.
- 35 7. In a telephone exchange system, a plurality of subscribers' lines, a plurality of link circuits for interconnecting said subscribers' lines, an operator's telephone set, automatic switching means adapted to include said operator's set with the link circuits, automatic switching means for preventing the inclusion of said operator's set 40 with more than one of said link circuits at the same time, a talking machine, and means controlled by said automatic switching means adapted to include said talking machine with a link circuit for a predetermined interval of time. 50
- 55 8. In a telephone exchange system, subscribers' lines, link circuits for interconnecting said subscribers' lines, an operator's telephone set, means for automatically including said operator's telephone set with a link circuit used to answer a calling subscriber, means for automatically preventing the inclusion of said operator's set with another link circuit connected to answer a second subscriber's line during the time the operator's telephone set is included with said link circuit used to answer the first mentioned subscriber's line, a talking machine, and switching means adapted to automatically include said talking machine with said 60 second subscriber's line immediately following the completion of a connection for said first subscriber's line. 65
- 70 9. A telephone exchange system comprising telephone lines, a link circuit for interconnecting the lines, an operator's telephone set, means responsive to the connection of the link circuit with one of the lines as a calling line to connect therewith the operator's telephone set, a second link circuit connected with another line as a calling line, a talking machine, a ringing key associated with the first of said link circuits for use in signaling a called line, means actuated upon the operation of said ringing key after the connection of the first link circuit with one of the lines as a called line to connect the talking machine with the second link circuit, and means responsive to the connection of the first link circuit with the 75 called line to disconnect the operator's telephone set from the first link circuit and to connect it with the second link circuit. 80
- 85 45 10. In witness whereof, I hereunto subscribe my name this 28th day of February, A. D. 95 1916.

HENRY P. CLAUSEN.
